STOKER FEEDING APPARATUS

Alfred De Los Sinden, Aurora, Ill., assignor to
 Redler Conveyor Company, Quincy, Mass., a
 corporation of Massachusetts

Application April 3, 1940, Serial No. 327,668

9 Claims. (Cl. 114—0.5)

This invention relates to a stoker feeding apparatus for supplying fuel to the stokers of a ship.

The invention has for an object to provide novel and improved apparatus of the character specified in which provision is made for withdrawing the fuel from the bottom of the bunkers of the ship, elevating the material thus withdrawn and thereafter distributing the fuel to a plurality of stokers in a simple and efficient manner.

A further object of the invention is to provide novel and improved apparatus of the character specified having provision for maintaining the stokers of a ship supplied with fuel and in which provision is made for controlling the operation thereof whereby to stop the feed of the fuel when the stokers are filled and to automatically start the feeding operation when the supply in the hoppers has been diminished.

With these general objects in view and such others as may hereinafter appear, the invention consists in the stoker feeding apparatus and in the various structures, arrangements and combinations of parts hereinafter described and particularly defined in the claims at the end of this specification.

In the drawings which illustrate the preferred embodiment of the invention, Fig. 1 is a transverse sectional view of a ship embodying the present invention; Fig. 2 is a plan view of the stoker feeding apparatus shown in Fig. 1; Fig. 3 is a side elevation in cross-section taken on the line 3—3 of Fig. 1; Fig. 4 is an enlarged detail view in cross-section on the line 4—4 of Fig. 1; Fig. 5 is a detail view in perspective of a section of the conveying element preferably employed in the present feeding apparatus; and Fig. 6 is a sectional view of a portion of the control mechanism, to be referred to.

In general, the present invention contemplates a novel and improved stoker feeding apparatus adapted to withdraw the fuel from the bottom of the bunkers which are arranged upon either side of the ship and to distribute the fuel thus withdrawn to a plurality of stokers disposed between the bunkers. In the preferred embodiment of the invention, the fuel is permitted to flow by gravity from the bottom of the bunkers into a conveying unit which is adapted to elevate the fuel and convey it horizontally to be distributed to the stokers.

The conveying apparatus preferably employed may comprise a dual unit having a portion extending into and adapted to withdraw fuel from

5 a bunker disposed on one side of the ship and to deliver the fuel to the stoker hoppers. A duplicate conveyer portion of the dual unit is arranged to deliver fuel to the stokers from a bunker disposed on the other side of the ship. In operation, either conveyer portion may be operated independently of the other to maintain all of the stokers supplied with fuel. The fuel bunkers are arranged symmetrically upon port and starboard sides of the ship so that the fuel may serve as ballast to keep the ship trim in the water. Thus, fuel may be withdrawn from either bunker, as required, to keep the ship balanced and to prevent any list of the ship.

10 15 Provision is also made in the preferred embodiment of the invention for automatically controlling the operation of the conveyers, whereby to terminate the feeding operation of the conveyer when the last hopper in the group is filled and to again initiate the operation thereof when the supply in such hopper is diminished, as will be hereinafter described.

15 Referring now to the drawings, 10 represents a ship which is provided with duplicate bunkers 12, 25 14 arranged symmetrically upon the port and starboard sides of the ship. The power plant of the ship, which may include steam boilers 16, 18, is provided with a plurality of automatic stokers 20, 22. The stokers 20, 22 are provided with hoppers 24, 26 respectively, which are arranged 20 in alignment transversely of the ship and between the duplicate bunkers 12, 14. The dual conveying unit, indicated generally by the numeral 25 comprises, in effect, two independently operated conveying units 28, 30 arranged parallel to each other and adapted to withdraw the fuel from their respective bunkers to maintain all of the stoker hoppers supplied with fuel.

25 30 35 Since each conveying unit 28, 30 of the dual apparatus is similar in construction and mode of operation, a description of one will suffice for both. As herein shown, the conveying unit 28 comprises a casing having a loop portion 32 which is provided with an inlet 34 communicating with the bottom of the fuel bunker 12 and through which the fuel is arranged to flow by gravity into the conveyer. The material thus withdrawn is elevated through an upright leg 36 of the casing and around a corner into a horizontal run 38 by an endless conveying element, indicated generally at 40. The horizontally extended run 38 passes over the top of each stoker hopper 24, 26 and is provided with a plurality of 40 45 50 openings 42 in communication therewith through

which the material is permitted to flow by gravity to keep the hoppers filled.

In the illustrated and preferred embodiment of the invention, the conveying element 40 may comprise a plurality of pivotally and detachably connected spaced flight members 44 of open construction and of general U-shape, as shown in detail in Fig. 5. Each flight member 44 is provided with a rigid connecting member 46 having at one end a hollow hub 48 and at the other end an enlargement 50 capable of being received within the hollow hub of a succeeding flight to pivotally connect the units together. The endless conveying element thus constructed is adapted, in cooperation with the walls of the casing through which it is drawn, to convey the material therethrough in a continuous stream.

As herein shown, the endless conveying element 40 is arranged to be driven by an electric motor 52 mounted on top of the horizontally extended portion of the casing and which is connected by a chain and sprocket drive 54 to the conveyer shaft 56 upon which a driving sprocket 58 is mounted. The endless conveying element 40 is arranged to pass over the sprocket 58 by which it is drawn through the casing. After passing through the lower or working run 38 of the conveyer, the endless conveying element is arranged to pass over the sprocket 58 and into an upper or return run 62 of the conveyer and over an idler sprocket or drum 64 disposed in the outer corner of the casing by which the conveying element is guided into the loop portion 32 of the conveyer. In passing around the corner portion of the working run of the conveyer, the conveying element 40 is arranged to be supported by an anti-friction device which may comprise a rotatable drum 70 which cooperates with the conveying element as the latter is carrying the load of material around the corner from the vertical run 36 into the horizontal run 38 of the casing. Any material which may leak by the rotatable drum 70 may be returned to the stream of material by being directed downwardly through a conduit 72 and into the return run, as illustrated in Fig. 1.

As above described, a duplicate conveying unit 30 is provided to withdraw the material from the bunker 14 on the starboard side of the ship and to distribute the fuel thus withdrawn to the stoker hoppers 24, 26. The conveyer 30 runs alongside of and parallel to the conveyer 28 and the horizontally extended portions of each conveyer are arranged in contiguous relationship to form a unitary casing, as illustrated in cross-section in Fig. 4, the separate paths of the conveyers being divided by a partition wall 74. The horizontally extended leg of the conveyer 30 is provided with a plurality of openings 76 disposed in alignment with and forming a continuation of the openings 42 in the conveying unit 28 and which communicate with the stoker hoppers 24, 26. A separate motor 75 is provided to drive the conveyer unit 30.

From the description thus far, it will be observed that in the operation of the conveying apparatus, when the conveying unit 28 is in operation, the material being conveyed through the horizontal run 38 will flow into the adjacent hopper 24 until it is filled. Thereafter, the material will be carried across the filled hopper and be fed into the next succeeding hopper in the line, and will continue along in this manner until all the hoppers 24 and 26 are filled whereupon the conveying apparatus is brought to rest.

Likewise, when the conveying unit 30 is in operation, and the unit 28 is idle, all of the hoppers may be filled in a similar manner.

In the illustrated embodiment of the invention, provision is made for controlling the operation of the conveyers to discontinue the feed when the last hopper in the line is supplied with fuel. As herein shown, see Fig. 6, such controlling mechanism may include a diaphragm switch 80 disposed in the final hopper and which may be operated to break the circuit to the driving motor by the pressure of the material within the hopper. The control switch may comprise a diaphragm 82 composed of leather or similar substance which is supported by an annular member 84 over an opening in the hopper. The central portion of the diaphragm is connected by a link 86 to a pivotally mounted lever 88 upon which the mercury switch 90 is secured. The diaphragm 82 is normally caused to bulge inwardly, as shown by the dotted lines in Fig. 6, by a spring 92 connected at one end to the switch lever 88 and at the other end to a stationary switch supporting member 94. In the normal or inwardly extended position of the diaphragm, the mercury switch 90 is held in a horizontal position to maintain the circuit to the motor closed to operate the conveyer. When the final hopper in the line is filled, the pressure of the material therein causes the diaphragm to bulge outwardly to rock the switch into an inclined position whereby the circuit to the motor is opened to terminate the feeding operation.

As illustrated in Fig. 1, a separate control circuit 100, 102 is provided for each conveying unit 28, 30 respectively. The circuit 100, which is arranged to control the operation of the motor 52 for the conveying unit 28 is provided with a lead 104 from the main circuit to the motor and a lead 106 from the motor to the diaphragm switch 80 which is disposed in the end hopper 28. A lead 108 from the diaphragm 80 to the main circuit is provided with a manually operated switch 110 by which the circuit 100 may be rendered inoperative when the conveyer 28 is idle and the conveyer 30 is in operation. The circuit 102 arranged to control the operation of the motor 75 of the conveying unit 30 is provided with a similar diaphragm switch 80 in the end hopper 24 and a manually operated switch 112, as shown in Fig. 1.

In the event that the final stoker in the line is shut down for any reason so that the diaphragm switch 80 is inoperative to effect opening and closing of the circuit, the circuit may be shunted as indicated by dotted lines at 114 in order to permit a conveying unit to be controlled manually by the switches 110, 112.

From the above description it will be observed that the dual stoker feeding apparatus of the present invention is adapted to withdraw fuel from either bunker and to distribute the fuel thus withdrawn to all of the stoker hoppers. It will be apparent that the present structure may be operated to feed material simultaneously from each bunker if desired by merely changing the controls, whereby the hoppers may receive material through the openings 42, 76 at the same time, when it is desired to fill the hoppers quickly.

While the preferred embodiment of the invention has been herein illustrated and described, it will be understood that the invention may be embodied in other forms within the scope of the following claims.

Having thus described the invention, what is claimed is:

1. For use in a ship having bunkers disposed symmetrically upon port and starboard sides of the ship and arranged when supplied with fuel to serve as ballast to keep the ship trim in the water and having a plurality of stoker hoppers arranged in substantial alignment transversely of the ship between said bunkers, apparatus for supplying flowable solid fuel to said stoker hoppers comprising dual conveying apparatus adapted to withdraw fuel from either of said bunkers and to distribute it to all of said stokers whereby the ship may be kept on an even keel, said dual apparatus including two conveyers arranged side by side in contiguous relation and traveling in opposite directions, each conveyer being arranged to supply fuel to each of said hoppers. 5
2. For use in a ship having bunkers disposed upon both sides of the ship and a plurality of stoker hoppers arranged transversely of the ship between said bunkers, apparatus for supplying flowable solid fuel to said stoker hoppers comprising dual conveying apparatus having portions extending within and adapted to withdraw fuel from either of said bunkers and to distribute the fuel thus withdrawn to all of the stokers, said dual apparatus including two conveyers arranged side by side in contiguous relation and traveling in opposite directions, each conveyer being arranged to supply fuel to each of said hoppers. 10
3. For use in a ship having bunkers disposed upon both sides of the ship and a plurality of stoker hoppers arranged transversely of the ship between said bunkers, apparatus for supplying flowable solid fuel to said stoker hoppers comprising dual conveying apparatus comprising two independently operated conveying units arranged side by side in contiguous relation and traveling in opposite directions, each of said conveying units comprising a casing, an endless conveying element traversible through the casing, each casing having a portion provided with an inlet in communication with the bottom of a bunker and adapted to withdraw fuel therefrom by gravity, an upright portion through which the fuel is elevated, and a horizontal portion extending transversely of the ship each of said conveyers being provided with a plurality of outlets communicating with each of said stoker hoppers and through which said fuel is delivered. 15
4. For use in a ship having bunkers disposed upon both sides of the ship and a plurality of stoker hoppers arranged in alignment transversely of the ship between said bunkers, apparatus for supplying flowable solid fuel to said stoker hoppers comprising dual conveying apparatus comprising two independently operated conveying units arranged side by side in contiguous relation and traveling in opposite directions, each of said conveying units comprising a casing, an endless conveying element traversible through the casing, each casing having a portion provided with an inlet in communication with the bottom of a bunker and adapted to withdraw fuel therefrom by gravity, an upright portion through which the fuel is elevated, and a horizontal portion provided with a plurality of outlets communicating with each of said stoker hoppers and through which said fuel is delivered and independent control means for each of said conveying units adapted to terminate the operation of a unit when the final stoker hopper in the line is supplied with fuel and to initiate the operation of the unit when the supply in said final stoker hopper is diminished. 20
5. For use in a ship having bunkers disposed upon both sides of the ship and a plurality of stoker hoppers arranged transversely of the ship between said bunkers, apparatus for supplying flowable solid fuel to said stoker hoppers comprising dual conveying apparatus comprising two independently operated conveying units arranged side by side in contiguous relation and traveling in opposite directions, each of said conveying units comprising a casing, an endless conveying element comprising a plurality of spaced flight members of open construction traversible through the casing, each casing having a portion provided with an inlet in communication with the bottom of a bunker and adapted to withdraw fuel therefrom by gravity, an upright portion through which the fuel is elevated, and a horizontal portion provided with a plurality of outlets communicating with each of said stoker hoppers and through which said fuel is delivered. 25
6. For use in a ship having bunkers disposed upon both sides of the ship and a plurality of stoker hoppers arranged in alignment transversely of the ship between said bunkers, apparatus for supplying flowable solid fuel to said stoker hoppers comprising dual conveying apparatus comprising two independently operated conveying units arranged side by side in contiguous relation and traveling in opposite directions, each of said conveying units comprising a casing, an endless conveying element comprising a plurality of spaced flight members of open construction traversible through the casing, each casing having a portion provided with an inlet in communication with the bottom of a bunker and adapted to withdraw fuel therefrom by gravity, an upright portion through which the fuel is elevated, and a horizontal portion provided with a plurality of outlets communicating with each of said stoker hoppers and through which said fuel is delivered and independent control means for each of said conveying units adapted to terminate the operation of a unit when the final stoker hopper in the line is supplied with fuel and to initiate the operation of the unit when the supply in said final stoker hopper is diminished. 30
7. For use in a ship having bunkers disposed symmetrically upon port and starboard sides of the ship and arranged when supplied with fuel to serve as ballast to keep the ship trim in the water and having a plurality of stoker hoppers arranged transversely of the ship between said bunkers, apparatus for supplying flowable solid fuel to said stoker hoppers comprising dual conveying apparatus adapted to withdraw fuel from either of said bunkers and to distribute it to all of said stokers, said dual conveying apparatus comprising two independently operated conveying units arranged side by side in contiguous relation and traveling in opposite directions, and independent control means including an electric circuit and a diaphragm switch in the circuit for each of said conveying units adapted to terminate the operation of a unit when the final stoker hopper in the line is supplied with fuel and to initiate the operation of the unit when the supply in said final stoker is diminished. 35
8. For use in a ship having bunkers disposed symmetrically upon port and starboard sides of the ship and arranged when supplied with fuel to serve as ballast to keep the ship trim in the water and having a plurality of stoker hoppers arranged transversely of the ship between said 40
9. For use in a ship having bunkers disposed symmetrically upon port and starboard sides of the ship and arranged when supplied with fuel to serve as ballast to keep the ship trim in the water and having a plurality of stoker hoppers arranged transversely of the ship between said 45
10. For use in a ship having bunkers disposed symmetrically upon port and starboard sides of the ship and arranged when supplied with fuel to serve as ballast to keep the ship trim in the water and having a plurality of stoker hoppers arranged transversely of the ship between said 50
11. For use in a ship having bunkers disposed symmetrically upon port and starboard sides of the ship and arranged when supplied with fuel to serve as ballast to keep the ship trim in the water and having a plurality of stoker hoppers arranged transversely of the ship between said 55
12. For use in a ship having bunkers disposed symmetrically upon port and starboard sides of the ship and arranged when supplied with fuel to serve as ballast to keep the ship trim in the water and having a plurality of stoker hoppers arranged transversely of the ship between said 60
13. For use in a ship having bunkers disposed symmetrically upon port and starboard sides of the ship and arranged when supplied with fuel to serve as ballast to keep the ship trim in the water and having a plurality of stoker hoppers arranged transversely of the ship between said 65
14. For use in a ship having bunkers disposed symmetrically upon port and starboard sides of the ship and arranged when supplied with fuel to serve as ballast to keep the ship trim in the water and having a plurality of stoker hoppers arranged transversely of the ship between said 70
15. For use in a ship having bunkers disposed symmetrically upon port and starboard sides of the ship and arranged when supplied with fuel to serve as ballast to keep the ship trim in the water and having a plurality of stoker hoppers arranged transversely of the ship between said 75

bunkers, apparatus for supplying flowable solid fuel to said stoker hoppers comprising dual conveying apparatus adapted to withdraw fuel from either of said bunkers and to distribute it to all of said stokers, said dual conveying apparatus comprising two independently operated conveying units arranged side by side in contiguous relation and traveling in opposite directions, and independent control means including an electric circuit and a diaphragm switch in the circuit for each of said conveying units adapted to terminate the operation of a unit when the final stoker hopper in the line is supplied with fuel and to initiate the operation of the unit when the supply in said final stoker is diminished, and a manually operated switch in each of said circuits for rendering one of the circuits inoperative when the other is in operation.

9. For use in a ship having bunkers disposed symmetrically upon port and starboard sides of the ship and arranged when supplied with fuel to serve as ballast to keep the ship trim in the

water and having a plurality of stoker hoppers arranged transversely of the ship between said bunkers, apparatus for supplying flowable solid fuel to said stoker hoppers comprising dual conveying apparatus adapted to withdraw fuel from either of said bunkers and to distribute it to all of said stokers, said dual conveying apparatus comprising two independently operated conveying units arranged side by side in contiguous relation and traveling in opposite directions, and independent control means including an electric circuit and a diaphragm switch in the circuit for each of said conveying units adapted to terminate the operation of a unit when the final stoker hopper in the line is supplied with fuel and to initiate the operation of the unit when the supply in said final stoker is diminished, and a manually operated switch in each of said circuits whereby to enable said conveying units to be operated independently of said control means when the final stoker in the line is cut out.

ALFRED DE LOS SINDEN.
